PHOTOGRAPHIC FLASH UNIT

Wallace A. Monson, Golden Valley, Minn., assignor to Minneapolis-Honeywell Regulator Company, Minneapolis, Minn., a corporation of Delaware

Filed June 22, 1961, Ser. No. 65,683

Term of patent 14 years

(Cl. D61—1)

FIGURE 1 is a perspective view of a photographic flash unit showing my new design;

FIGURE 2 is a front view,

FIGURE 3 is a back view,

FIGURE 4 is a top view,

FIGURE 5 is a bottom view, and

FIGURE 6 is a left side view.

The essential features of my design reside in the combination on a photographic flash unit of symmetrically shaped side walls, each end of which terminates at an inwardly directed V-shaped groove of balanced proportion, and the apex of each of the grooves defining a central region to which a handle is centrally located, one end of the handle being attached to each of the side walls, all as shown.

I claim:

The ornamental design of a photographic flash unit, substantially as shown and described.
